UNITED STATES PATENT OFFICE.

GEORG UHL, OF NEW YORK, N. Y.

FIREARM-SUPPORT.

1,112,732.

Specification of Letters Patent.

Patented Oct. 6, 1914.

Application filed May 7, 1914. Serial No. 836,857.

To all whom it may concern:

Be it known that I, GEORG UHL, citizen of the United States of America, residing at New York, in the county of New York and State of New York, have invented certain new and useful Improvements in Firearm-Supports, of which the following is a specification.

The present invention relates to means for supporting a fire arm during operation in order to steady the aiming, and has for its object to provide a gun rest which can be removably attached to the gun to extend alongside of it when not in use and when detached and unfolded to support the gun during operation.

I accomplish my object by providing an extensible member having a socket connected to it by a swivel joint and serving to engage the gun. The extensible member freely engages with its socket the barrel of the gun and is strapped or otherwise removably secured to the gun to extend alongside of the barrel thereof when not in use. The extensible member when detached from the gun can be swung around the swivel joint and adjusted to the desired height. To render the aiming more steady while shooting in lying position, I provide an additional foldable rest.

My invention will be fully understood by reference to the accompanying drawing in which similar reference characters denote corresponding parts and in which—

Figure 1 is an elevation of my gun support as applied to the gun, the dotted lines indicating the support unfolded and extended; Fig. 2 is an elevation of the extended gun support shown in position of use; Fig. 3 is an enlarged elevation of a portion of the extensible gun support; Fig. 4 is an enlarged cross section on line 4—4 of Fig. 3; Fig. 5 is an enlarged similar view as Fig. 1 showing the additional foldable rest unfolded and supporting the gun and Fig. 6 is a front view of the gun support and the unfolded rest.

In the drawing *a* denotes a fire-arm or gun and *b* is the gun support. The latter consists of a plurality of telescopically engaging sections *b'*, *b²*, *b³* permitting the extension of the member *b* to any desired height or length. At one end the extensible member has attached to it by a swivel joint *c'* an adjustable yoke or socket adapted to freely engage around the barrel of the gun, as

clearly shown in Figs. 2 and 6. The swivel joint between the loop-shaped part *c* and the member *b'* is formed by a pin rotatively mounted in a sleeve *b^a* which is fixed to the free end of the section *b'*. Fixed to the lower end of the member *b³* is a foldable base or foot *b⁴*. This foot consists of side bars hinged or pivoted at *b⁵* to the free end of the innermost section *b³* of the member *b* and connected by a foldable cross piece *b⁶* hinged to the opposite ends *b⁷* of the side bars. In unfolded position this foot has the shape of a triangle and serves as a rest for the member *b* in upright position. For locking the sections in adjusted position I provide each inner section with a pin *e* which is adapted to project through a longitudinal slot *b^b* provided in the surrounding section. I also provide each slotted section with a plurality of cross notches *b^c* which are spaced apart according to the different adjustments desired, and which are adapted to receive the pin *e* in adjusted position. Each inner section is also provided with a leaf-spring *f* which is displaced relative to the pin *e* so that normally, when the pin *e* is within the slot *b^b*, it will be compressed by the surrounding section; but when the section carrying the pin *e* is turned to engage the latter into the notch *b^c*, it will be brought into the range of the longitudinal slot *b^b* in which it will expand and form an obstruction or stop locking the sections in adjusted position.

In order to provide for a support of the gun when shooting in lying position I provide an auxiliary base. This base consists of a part *d* of semi-cylindrical cross section and of a diameter which conforms with that of the section *b'*. At its ends the part *d* has curved extensions *d²* the free edges of which are slightly bent inwardly so as to snap around the section *b'* when the part *d* is folded over the latter. This part *d* is hinged or otherwise pivotally connected at *d^a* to a rod *d'* which at its opposite end is loosely mounted around the pin *c'* to be capable of swinging thereon. The base or rest can thus be swung around the hinge point *d^a* and the pin *c'* and is thus rendered foldable.

The gun support is adapted to be removably attached to the gun as by a strap *g* or the like as indicated in Figs. 1 and 5, so as to extend alongside the barrel and to engage with its socket the mouth end of the barrel as indicated in Figs. 2 and 6. For

shooting in standing or kneeling position the extensible member *b* is detached and swung around into upright position as indicated by dotted lines in Fig. 1 and adjusted according to the height desired. The swivel joint between the socket and the member *b'* and the hinge joint of the foot *b'* permit the lowering and raising of the gun according to the firing position. When firing in lying position the member *b* need not be detached from the gun. Instead the base *d* or rest is unfolded and swung into upright position as shown in Figs 5 and 6.

What I claim and desire to secure by Letters Patent is:

15. 1. A gun support, consisting of a longitudinally extensible member, a socket thereon for the engagement of the gun and a foldable base or foot at the lower end of said member.
20. 2. A gun support, consisting of a longitudinally extensible member adapted to be removably attached to the gun, a socket on said member for the engagement of the gun and a foldable base serving to support the gun when shooting in lying position, said base being connected to said member and

adapted to engage around said member when in folded position.

3. A gun support, consisting of a longitudinally extensible member adapted to be removably attached to the gun, a socket on said member to engage the gun, a foldable foot or base to support said member in upright position and a foldable base to support the gun when shooting in lying position, said base being connected to said member and adapted to engage around the latter when in folded position.

4. A gun support, consisting of an extensible member, a socket thereon to engage the gun and a foldable base serving to support the gun when shooting in lying position, said base being pivotally connected to said socket and adapted to normally engage around said member when in folded position.

In testimony whereof I affix my signature in presence of two witnesses.

GEORG UHL.
